United States Patent Office

Des. 185,211
Patented May 19, 1959

185,211

SPOON OR SIMILAR ARTICLE

Kae E. Jones, New York, N.Y., assignor to Welling Ware,
Inc., New York, N.Y., a corporation of New York

Application August 23, 1957, Serial No. 47,490

Term of patent 7 years

(Cl. D54—12)

Fig. 1 is a top plan view of a spoon or similar article, showing my new design.

Fig. 2 is a side view thereof.

Fig. 3 is a bottom plan view thereof.

Fig. 4 is a cross-sectional view taken on line 4—4 of Fig. 1, and drawn to an enlarged scale.

Fig. 5 is a cross-sectional view taken on line 5—5 of Fig. 1, and drawn to an enlarged scale.

The essential features of my design resides in the handle portion as shown in full lines on the drawing.

I claim:

The ornamental design for a spoon or similar article, substantially as shown and described.
